United States Patent Office

Des. 191,215
Patented Aug. 29, 1961

191,215

DISH OR THE LIKE

Paul A. Schroeder, Cincinnati, Ohio, assignor to Plastic Specialties, Inc., Cincinnati, Ohio, a corporation of Ohio

Filed Apr. 10, 1961, Ser. No. 64,677

Term of patent 14 years

(Cl. D44—15)

FIG. 1 is a perspective view of a dish showing my new design.

FIG. 2 is a sectional view taken on line 2—2 of FIG. 1.

FIG. 3 is a top plan view thereof.

I claim:

The ornamental design for a dish or the like, as shown.
